UNITED STATES PATENT OFFICE.

JAMES HOWARD TAYLOR AND IZORA TAYLOR, OF PHILADELPHIA, PENNSYLVANIA.

CORSET.

1,240,510.

Specification of Letters Patent. Patented Sept. 18, 1917.

Application filed February 24, 1915. Serial No. 10,172.

To all whom it may concern:

Be it known that we, JAMES HOWARD TAYLOR and IZORA TAYLOR, both citizens of the United States, residing in the city and county of Philadelphia, State of Pennsylvania, have invented a new and useful Corset, of which the following is a specification.

Our invention relates to the general class 10 of corsets for women which are worn in conjunction with brassières or breast supporters.

In prevailing modes, the upper edges of the corsets worn by women are below the 15 breasts and the corsets are designed to compress the waist and hips.

Obviously, in the use of this type of garment the breasts are unsupported and it has been a common practice for the user to wear 20 a brassière of any of the usual kinds, the lower or waist portion of which in its use is either outside of or else within, that is, surrounded or inclosed by the upper portion of, the corset, while in either mode of wearing 25 its upper or edge portion extends above the breasts and either directly and evenly across from arm pit to arm pit or in upward curvature from the center outwardly on each side to partly embrace the shoulders above the 30 level of the arm pits and to be provided with shoulder straps extending to its upper back portion.

The object of our invention is to so combine a corset with a brassière that each 35 serves its intended purpose, while by their union advantages, economy, durability and comfort are secured, and the entire composite garment is one that possesses many 40 advantages which render it readily, and in many instances more easily, salable than would be the case were the two separate.

With the object, therefore, of making a serviceable useful and relatively inexpensive composite garment of the character recited, we have invented a combined corset and brassière a typical and at present preferred embodiment of which is represented 45 in the accompanying drawing and herein-after-described, the special features of which 50 we claim as novel being definitely specified in the claiming clauses.

In the drawing, Figure 1 is a view in perspective of the figure of a woman in the act of putting on a corset embodying our invention.

Figs. 2 and 3 are fragmentary, elevational views of the upper portions of the back of the corset,—that in Fig. 2 being assumed to be the right hand back portion and that in Fig. 3 the left hand back portion, to each of 60 which is shown as connected one member or half part of our brassière which in Fig. 2 is represented as lying flat against the back portion of the corset and in a position to be thrown inwardly and around the right 65 breast of the wearer, while the other member or that shown in Fig. 3 is shown as folded backward, outwardly and in the opposite position to that which its counterpart occupies in Fig. 2, and in a position to be 70 thrown over on the line of its stitching 12 to the corset back and to the right of said Fig. 3.

Fig. 4 is a fragmentary, sectional top plan assumed to be taken in a horizontal plane of 75 the breasts.

Figs. 5 and 6 are fragmentary, inside elevations of the component elements of our brassière, provided with ribbons, shown untied in Fig. 5 and tied in Fig. 6 and which 80 when tied, for instance into a bow as shown in Fig. 6, draw together the two members which constitute the brassière proper and cause them to each assume semispherical or globular shape, so as to permit of their use 85 to give the effect of larger breasts than the wearer may possess or to constitute them as false breasts.

Similar numerals of reference indicate 90 corresponding parts.

In the drawings, 1 designates a corset provided with the usual front steels or clasps 2 and back eyeleted steels 3, for the lacings, and with bonings 4,—all of any preferred type.

5 is the right front member and 6 the left front member of the brassière, to one of which—the right as shown—are attached the edge hooks or clasps 7, and to the other—the left as shown—eyes 8 for said hooks.

The two members of the brassière are preferably opposite counterparts, of similar contour and each preferably provided with stiffening or shaping bones 9.

10 are connecting tapes or webs of flexible and preferably slightly elastic material, and made in a plurality of parts as the tapes shown, which are outwardly sewed or otherwise connected and attached to the inner edges of the members of the brassière,

and are inwardly or at their inner edges connected with the upper back portions of the corset by lines of stitching 12.

In Figs. 5 and 6,—13 and 14 designate 5
5 ribbons connected with the interior surfaces
of the members of the brassière by being
sewed to them as indicated, and which are
respectively adapted as to their free ends to
be tied together in bow knots 15, so as to
10 draw together, or, so to speak, circumferentially
curve in the fabric of which the mem-
bers of the brassière are composed and cause
said members by reason of the stiffening 9
to assume and retain a semi-spherical or out-
15 wardly expanded form.

It will now be understood that the mem-
bers which compose our brassière are con-
nected, preferably flexibly, with the upper
20 back portions of the corset proper, and are
adapted in the putting on of the composite
garment by the wearer to be brought to-
gether as to their hook and eye provided
edges over the breast and chest of the wearer
and hooked or connected as shown in Fig. 1.
25 It will be further understood that after
this has been done, the corset proper, which
in our garment encircles or overlaps the
brassière, is then drawn together and fas-
tened in any usual manner, and in the con-
30 struction illustrated by being hooked to-
gether as to its front edges and laced as to
its back edges.

In addition to many other advantages
which obviously inhere in our invention, is
35 the additional advantage of not having the
body of the wearer entirely encircled or en-
veloped with and by the brassière as well as
with and by the corset, and, therefore, of not
having double and unnecessary thicknesses
40 of material entirely around the body of the
wearer.

Although we do not limit ourselves to at-
taching each of the two members of the
brassière through the intervention of their
45 tapes or webs to the back portion of the

corset in the relative positions with respect
to its back steels shown in the drawings, we
prefer so to attach them, with the result
that while the brassière subserves its in-
tended function of supporting the breasts of 50
the wearer, it does not completely encircle
her body so as, as already explained, to in-
duce unnecessary thickness and consequent
warmth.

It will now be apparent that we have de-
vised a novel and useful combined corset
and brassière which embodies the features
of advantage enumerated as desirable in the
foregoing description, and that while in the
present instance we have shown and de-
scribed preferred embodiments of our invention
which in practice give satisfactory and
reliable results, it is to be understood that
the invention as such or broadly considered
is susceptible of modification in various par-
ticulars without departing from its spirit
or scope or sacrificing any of its advantages.
Having thus described our invention what
we claim as new and desire to secure by Let-
ters Patent, is:

An article of manufacture comprising the
combination of a corset with a brassière
formed of two members, the front edges of
which are adapted to be secured together,
an extensible fabric connecting the back
edges of each member to the inner back portion
75 of the corset, each member extending a
suitable distance above and below the upper
edge of the corset, whereby when the corset
is in place said two members will embrace 80
the bust, will be held in position by the close
engagement of the corset therewith, and will
permit the free movement of the upper por-
tion of the corset in a direction away from
the body of the wearer.

JAMES HOWARD TAYLOR.
